ELECTRON DISCHARGE DEVICE

Bernard Salzberg, East Orange, N. J., assignor, by
mesne assignments, to Radio Corporation of
America, New York, N. Y., a corporation of
Delaware

Application May 29, 1936, Serial No. 82,453

4 Claims. (Cl. 250—27.5)

My invention relates to electron discharge tubes, more particularly to improvements in seals and the method of sealing in radial lead-in wires in the side walls of the envelope of the tube.

In one form of electron discharge device particularly useful at high frequencies and commonly referred to as the "acorn" tube, the electrode mount assembly is provided with radial lead-ins. The mount is positioned within an envelope, usually carbon coated on the inside and which prior to sealing comprises a pair of cup-shaped members each provided with an annular lip and between which lips the radial leads extend and are sealed. In assembling the tube the 5 mount is positioned to extend downwardly within one of the cup-shaped members so that the radial leads rest on the lip of the cup-shaped member. The other cup-shaped member is then positioned over the leads so that the lips on the cup-shaped members register with each other. 10 Fires are then played on the lips until the glass flows around the leads to seal the lips. The lips may then be pressed together in a die, for example, to provide an outwardly extending annular seal or press through which the radial leads extend. In some cases this method of sealing has introduced difficulties.

Due to the space which existed between the lips when the cup-shaped members and mount 15 were first assembled, the sealing fires would heat the parts of the mount within the cup-shaped members and cause oxidation of these members, resulting in gassy tubes and poor emission. If the mounts were not properly centered micro- 20 phonics would sometimes be introduced due to vibrations of mounts. Noise was sometimes caused by carbon particles which had been rubbed off the inside wall of the envelope when attempting to center the mounts.

The principal object of my invention is to provide an improved envelope construction for an 25 electron discharge device and a method of sealing a mount having radial leads within the envelope of the tube.

The novel features which I believe to be characteristic of my invention are set forth with particularity in the appended claims, but the invention itself will best be understood by reference to the following description taken in connection with the accompanying drawing in which Figure 1 is an exploded view of an electron discharge device made according to my invention, Figure 2 is a finished perspective view of the completed tube shown in Figure 1, and Figure 3 is a 30 bottom view of Figure 2.

Referring to Figures 1 and 2, the envelope 9 of the tube encloses and supports a unitary electrode mount assembly comprising an indirectly heated cathode 10 with the usual heater, a grid 11, and an anode 12, which may be a box-like structure made from sheet metal. The anode 12 has at each end extensions 13 which form shoulders for supporting electrode spacers 14 and 15 of insulation, such as mica, and preferably in the form of plates or discs transverse to the longitudinal axis of the tube. The extensions 13 are bent over against the mica plate members and may lie in slots in the edges of the plate members to rigidly secure the spacers to the anode so as to provide a rigid unitary electrode assembly. 5

Radially positioned stiff conductors 16, which serve as lead-ins and also as mount support wires extend through an annular press 17 in the wall of the tube 9 and as best shown in Figure 1 have 10 secured to their inner ends, preferably by welding, conductors 18 having one end threaded through the insulating disc or plate member 14 to secure the conductors 16 to the plate members and the other end electrically connected to 15 one of the electrodes mounted between the plates 14 and 15. The outer ends of conductor 16 serve 20 as tube contacts to be received in a properly designed socket. This construction eliminates the need of the usual reentrant stem and press and 25 materially reduces the overall dimensions of the tube.

While various methods may be used for assembling a tube of the type described, the usual procedure is after the electrodes have been assembled 30 between the insulating mica discs 14 and 15 to provide a unitary mount structure, the combined lead-ins and tube contacts 16 are secured to the mica disc spacer 14 and connected to the electrodes by means of conductors 18 in the manner 35 described above, one end of the conductor 18 being threaded through the mica disc 14 to secure conductors 16 to the mica and the other end of the conductor 18 being connected to an electrode. A 40 getter tab 19 may be secured to the anode. This 45 assembly is then positioned so that the mount extends downwardly within the cup-shaped portion 20 of the envelope 9 provided with annular lip 21, the lead-in conductors resting on the lip. A second cup-shaped portion 22 of the envelope 50 9 provided with an outwardly flared lip 23 is positioned over the leads so that the lips 21 and 23 register with each other. The outwardly flared lips facilitate assembly and sealing.

In accordance with my invention I provide 55

the lips of the cup-shaped members with depressions 24 and 25 which in assembly register with each other and receive the radial leads 16 when the mount and envelope are assembled prior to sealing. After the mount and cup-shaped members have been assembled heating fires are played on the lips until the lips become plastic and flow around the leads. The lips are then pressed together to insure proper sealing and to form the 10 annular press 17 through which the radial leads 16 extend. The tube is then exhausted through exhaust tube 26 and the envelope sealed off.

Because the leads and depressions on the lips of the cup-shaped members can all register in 15 only one position, the mount will always be properly centered and the possibility of contact between the carbon coating on the inside of the envelope and the mount during assembly is minimized, so that the chances of loose carbon particles and resulting noise is reduced to a minimum. Because the lips contact with each other when the mount and cup-shaped members are assembled, the sealing fires do not reach within 20 the envelope to oxidize the mount parts. This substantially eliminates gassy tubes due to oxidation. Because the mount is properly centered 25 vibration is minimized and microphonics are substantially reduced. The time necessary for assembly is also materially reduced.

30 While I have indicated the preferred embodiments of my invention of which I am now aware and have also indicated only one specific application for which my invention may be employed, it will be apparent that my invention is by no 35 means limited to the exact forms illustrated or the use indicated, but that many variations may be made in the particular structure used and the purpose for which it is employed without departing from the scope of my invention as set forth 40 in the appended claims.

What I claim as new is—

1. The method of assembling an electron discharge device having an envelope provided with an outwardly extending annular press, and a 45 mount with radial leads extending through and sealed into said annular press, including the steps of forming a pair of cup-shaped members

having annular lips, forming radially extending depressions in said lips, assembling the mount between the cup-shaped members with the depressions in registry and with the leads within said depressions whereby said mount and cup-shaped members can be assembled in only one relationship, and sealing said lips together to form an annular press through which said leads extend. 5

2. The method of assembling an electron discharge device having an envelope of vitreous material provided with an outwardly extending annular press and a mount with radial leads extending through and sealed into said annular press, including the steps of forming a pair of 15 cup-shaped members having outwardly flared annular lips forming radially extending depressions in said lips, assembling the mount between the cup-shaped members with the depressions in registry and with the leads within said depressions whereby said mount and cup-shaped members can be assembled in only one relationship, heating said lips to cause the vitreous material to flow around said leads and pressing said lips together to seal said lips together around the radially extending leads. 20 25

3. An envelope for an electron discharge device having a mount provided with radial leads, said envelope comprising a pair of cup-shaped members, outwardly flared annular lips on said cup-shaped members, and radially positioned depressions in each of said lips to be positioned in registry to receive the radial leads on said mount when the lips of said cup-shaped members are brought together for assembly. 30 35

4. An envelope for an electron discharge device having a mount provided with radial leads, said envelope comprising a pair of cup-shaped members, outwardly flared annular lips on said cup-shaped members, and radially positioned depressions in each of said lips to be positioned in registry to receive radial leads on said mount when the lips of said cup-shaped members are brought together for assembly, and an exhaust tube extending from one of said cup-shaped members. 40 45

BERNARD SALZBERG.
